UNITED STATES PATENT OFFICE.

AIKEN C. TAYLOR, OF RICHMOND, VIRGINIA, ASSIGNOR TO EMANUEL P. SUMMERFIELD, OF NORFOLK, VIRGINIA.

WINDOW.

1,171,367.

Specification of Letters Patent.

Patented Feb. 8, 1916.

Application filed December 21, 1914. Serial No. 878,412.

To all whom it may concern:

Be it known that I, AIKEN C. TAYLOR, a citizen of the United States, residing at Richmond, in the county of Henrico, State 5 of Virginia, have invented certain new and useful Improvements in Windows; and I do hereby declare the following to be a full, clear, and exact description of the invention, such as will enable others skilled in the art 10 to which it appertains to make and use the same.

This invention relates to windows of that class wherein a sash is adapted to be swung to a tilted position or vice versa, for the purpose 15 of regulating ventilation, to allow the glass pane of the window to be cleaned with safety and facility, and for other purposes, and is in the nature of an improvement upon the window forming the subject matter of 20 Patent No. 1,117,954, granted to Dorsett A. Davison, November 17, 1914.

While my invention in its broad aspects is based upon the same general principles as the structure of this Davison patent, yet it 25 differs therefrom in certain material respects and possesses certain manifest advantages thereover. For instance, instead of employing a substantially flat follower plate, a portion at least of which is visible 30 at all times, whether the window be open or closed, I make use of a spool-shaped follower, that is one having a pair of disk-like spaced flanges connected by a central barrel section, and this follower is so located within 35 and slides over a guide strip of such peculiar construction that it is entirely concealed within the strip when the window is closed. In addition, this follower is so constructed 40 as to have a cam-like binding action against the guide strip of the window frame when the sash is tilted, thereby assisting in holding the sash stationary in any position to which it may be tilted. Furthermore, instead of employing a substantially flat pivot 45 plate to which the window sash is pivoted, as is done in the Davison structure, I provide the sash strip connected to the window sash with a cam-like pivot stud rigid therewith, this stud having a cam-like binding 50 action against the adjacent flanges of the guide strip of the window frame when the sash is tilted, so that the sash will be held in such tilted open position as may be desired.

Another feature of advantage incident to my invention over the Davison construction, 55 is that when the window sash embodying my invention is completely closed, that is to say is in its vertical position in the frame, a weather-tight joint is formed between both the longitudinal edges of the sash strip and 60 both the longitudinal edges of the guide strip carried by the window frame, while in the Davison structure such weather-tight joint is formed between but one of the longitudinal edges of the sash strip, and one of 65 the adjacent longitudinal edges of the guide strip at the window frame.

Furthermore, in the present instance, when the sash is in its closed or vertical position, it is held locked or latched in such 70 position by means of a pin, which when it is desired to open the window, is depressed or moved out of locking position by contact with a short cam or tripping strip carried by the guide strip at the window frame, the 75 window sash being moved vertically a short distance to bring the pin into contact with the cam or tripping strip.

My invention consists in the construction, combination and arrangement of parts set 80 forth in and falling within the scope of the appended claims.

In the accompanying drawings: Figure 1 is a perspective view of a window embodying my invention, the lower sash being 85 shown as swung inward to a horizontal position. Fig. 2 is a detail perspective view of one side of a sash and showing the sash strip, the follower plate and the rigid pivot stud. Fig. 3 is a cross sectional view taken 90 through one side of the sash and the window frame, showing the sash in its vertical or closed position, with the latching pin holding 95 the sash in such position. Fig. 4 is a similar view showing the latching pin bearing against the cam or tripping strip which depresses the pin to permit the window to be swung or tilted, this depressing of the pin holding the window when it has been 100 slightly moved vertically. Fig. 5 is a perspective view of the bottom portion of one of the side bars of the sash and a portion of one of the guide strips of the window frame and showing the position of the sash strip 105 relative to the guide strip when the window is completely open or in horizontal po-

sition. Fig. 6 is a detail view of the lower portion of one of the side bars of the sash and illustrating a portion of the sash strip and the follower in elevation and the rigid 5 pivot stud in cross section. Fig. 7 is a detail view of a portion of one of the guide strips and showing the cam strip element formed thereon.

In the present instance in Fig. 1, I have 10 shown merely by way of illustration, a conventional form of window frame with the upper window sash closed and the lower sash tilted inward to open position. I will describe the invention as applied to the 15 lower sash, but it will, of course, be understood that it is applicable to the upper sash as well.

Referring now to the accompanying drawings in detail, the letter A indicates the 20 window frame as an entirety, and B indicates the upper and lower window sashes. Confining the description particularly to one sash, for instance the lower sash B, I provide at each side of the window frame a 25 longitudinally extending metallic guide strip which is indicated as an entirety by the letter G. This strip is preferably constructed of a single piece of metal which is bent longitudinally to form the flat rear 30 wall 1 through which nails or screws are passed to fasten the strip to the window frame. From this rear wall I project the side walls 2 and 3 of the strip. The side wall 2 includes the inwardly and longitudinally extending double or two-fold flange 4 and the inwardly extending longitudinal flange 5 which extends parallel with the flange 4, the wall 6 connecting these two flanges. Likewise the side wall 3 of the 35 strip is bent and folded to form the longitudinally and inwardly extending double flange 7 alining with and extending opposite to the double flange 4, the material at the free longitudinal edge portion of this wall 3 being then bent outward to form the flange 8. The flange 7 of the wall 3 is a guide strip G equipped with a curved cam or tripping strip 9 as shown in Fig. 7 for the purpose hereinafter mentioned. It is to be noted 40 that the longitudinal sections of the double flanges 4 and 7 are spaced apart and, being of sheet metal, possess a certain resiliency, so that when the adjacent sides of the window sash bear against these flanges they 45 will be first pressed inward and then sprung outward to form a weather tight joint with the sash strip, and this joint will be maintained irrespective of the contraction or expansion of the wood of either the window 50 frame or sash.

The window sash B is provided with the usual side bars b, each of which is longitudinally rabbeted at one side edge as at 10. To the outer face of each side bar I fasten 55 a longitudinally extending flat metallic

strip 11, hereinafter called the sash strip, the longitudinal side portion 12 of which overlies the rabbeted portion 10 of the side bar and forms a longitudinal groove 13 in conjunction therewith. The opposite longitudinal side edge of the strip 11 is turned inward to constitute the longitudinally extending flange 14 which forms a groove 15 in conjunction with the body of the strip. The flange 14 at its lower end terminates 75 short of the lower end of the strip, this forming a shoulder 16 for the purpose hereinafter set forth.

Rigid with and projecting inward from the lower end of each sash strip 11 is a pivot 80 stud p, including the shank section 17 and the heads 18. The shank 17 of the stud is approximately elliptical in cross section with the longer axis of the ellipse running vertically when the window sash is in its 85 vertical closed position. This pivot stud is adapted to project through the slot 4' formed by the confronting longitudinal edges of the flanges 4 and 7 when the parts are assembled, the shank 17 of the pivot 90 bearing against these confronting edges while the heads 18 bear against the sides of the flanges 4 and 7. It is to be noted that by means of these pivot studs p the window sash is pivotally connected with the guide 95 strips at the sides of the window frame, and when the sash is moved to its vertical position, the longer axis of the studs will also extend vertically so that the pivot studs themselves will not prevent the free sliding 100 of the sash strips and consequently the sash along the guide strips. When, however, the window is tilted inward or inclined as in opening the same for ventilation, as is shown in Fig. 1, the longer axes of the 105 shanks of the studs are turned crosswise of the guide strips and consequently the shanks 17 of the studs will tend to bind against the confronting longitudinal edges of the double flanges 4 and 7 of the guide strip and thus 110 the window may be held in any position to which it is tilted without the use of any additional latching means.

Pivotally connected as at 19, adjacent to the lower end portion of each sash strip 11, and above the pivot stud thereof, is a link 20, the free end of which carries a follower element 21. In the present instance this follower is made fast with the free end of its link, and is of spool-like form, that is to say is formed with the disk-like end flanges 22, connected by the barrel 23, which is also approximately elliptical in cross section. Each follower 21 is adapted to slide on the double flanges 4 and 7 of the 115 adjacent guide strip G, and to be guided thereby, one end flange 22 of the follower bearing against the inner faces of these flanges 4 and 7, while the flat end flange 22 of the follower bears against the outer faces 120 125 130

of these flanges 4 and 7, the barrel section 23 of each follower sliding between the confronting longitudinal edges of such flanges of the guide strip.

5 Socketed in each side bar of the window sash, as shown in Figs. 2 and 4, is a locking pin 24, the head of which extends through an opening 25 in the strip 11, a suitable spring 26 normally forcing the pin outward 10 into locking position. This pin is located above the point where the link 20 of the follower is pivoted to the sash strip. Now, when the window sash is swung to its closed or vertical position, the beveled end 27 of 15 the head of the pin will strike against the free longitudinal edge of the flange 8 of the guide strip and be momentarily pressed inward, but as soon as the window sash is completely closed with the sash bars in 20 parallelism with the guide strips of the window frame, and with the flange 14 of the sash strip receiving and engaging the flange 8 of the guide strip G, and with the free longitudinal edge of the flange 5 of the 25 guide strip seating in the groove 13 of the sash strip, this pin will spring out behind the flange 8 and interlocking therewith will hold the window in latched position against ordinary shocks and jars and prevent it 30 from accidentally swinging inward. When, however, it is desired to tilt the window to open the same, the closed window is first shifted vertically until the head of the locking pin 24 strikes and rides up over the cam 35 strip 9 of the guide strip G, and this will cause the locking pin to be depressed inward against the tension of the spring and permit the window to be opened or tilted inward, as the top surface of this cam strip 9 40 is substantially flush with the top edge of the flange 8.

One end of each sash cord *c* is attached at 28 to a link 29 connected with the adjacent follower element 21, the sash cord running over the pulleys in the frame to the 45 weights in the usual manner.

In connection with the followers I wish to call particular attention to the fact that the barrel section 23 of each follower is also 50 substantially elliptical in cross section, with the longer axis of the barrel extending vertically when the window sash is closed or in its vertical position, so that when the window is tilted or forced partially inward, the 55 outward pull of the link 20 upon its follower will tend to cause the latter to be pulled sidewise and also act to bind against the double flanges 4 and 7 and assist in holding the window in tilted position.

60 From the above description, taken in connection with the accompanying drawings, the construction and manner of employing my invention will be readily apparent to those skilled in the art. For each window sash two guide strips G are employed, one

at each side of the window frame. Likewise, of course, each window sash is equipped with two sash strips, each sash strip carrying a follower and a pivot stud. As before mentioned the pivot studs of the sash strips 70 are inserted into the longitudinal space or slot between the double or two-fold flanges 4 and 7, and when the window sash is in its vertical position, the longitudinal flange 5 of the guide strip G fits into the longitudinal 75 groove 13 formed by the plate 11 and the rabbeted edge of the sash bar, forming a weather-tight joint at this side of the window. Likewise the flange 8 of the guide strip G of the window frame interlocks with the longitudinal flange 14 of the sash strip, fitting into the groove 15 formed by this flange so that a weather-tight joint is formed by the flange 8 of the guide strip G and the flange 14 of the sash. Also in the 80 vertical or closed position of the window sash the locking pin will interlock with the flange and hold the window against accidentally opening or tilting, as heretofore described. Now, if it is desired to open and 85 tilt the window, the sash is first shifted upward vertically until each locking pin strikes the adjacent cam strip 9, when such locking pin will be depressed and the window may be tilted to open position. With 90 the tilting of the window, the pivot studs *p* are turned relative to the adjacent or longitudinal edges of the double or two-fold flanges 4 and 7, and the shanks of these 95 studs being elliptical in cross section will 100 thus bind with considerable friction against the edges of these double flanges so that the window may be maintained in any position to which it is tilted without employing any additional locking or holding means. 105

It will be noted that I have provided an exceedingly simple, yet efficient form of window of this class, and one wherein a weather-tight joint is formed between both the inner and outer faces of the sash bars 110 and the inner and outer faces of the guide strip. It will also be seen that when the window is swung to its horizontal position, or at an angle of ninety degrees relative to the window frame, the shoulder 16 at the 115 lower end of the flange 14 of the sash strip will strike against the adjacent portion of the flange of the guide strip G and prevent the window dropping or opening any farther. 120

Furthermore, it will be noted that both the follower elements and the pivot studs will lie and move within the confines of the sides of the guide strips at the window frame when the parts are assembled, and that the resiliency of the double fold flanges 4 and 7 insures that there will always be maintained a weather-tight, snug joint between the sash strips and the guide strips 125 when the window is closed. 130

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

10. What I claim is:

1. The combination with a window frame and a guide strip located at one side thereof said strip having side members bent centrally and longitudinally to form inturned double flanges, said strip also having longitudinally extending flanges at both the free longitudinal edges thereof, of a vertically swinging sliding sash, a sash strip extending longitudinally of one of the side bars of the sash, said sash strip having a longitudinally extending flange at one of its longitudinal edges, the opposite longitudinal edge of said sash strip overlying a longitudinally extending recess cut in the sash bar, the construction being such that when the sash is in its vertical, closed position, the flange of said sash strip will interlock with the adjacent flange at one side of the guide strip, the flange at the opposite side of the guide strip lying in the groove formed by the longitudinal edge portion of the sash strip and the recess in the sash bar, whereby a weather-tight joint is formed at both the inner and outer faces of the sash bar, and a follower connected with the sash and sliding upon the inturned double flanges of the guide strip of the frame.
2. The combination with a window frame and a guide strip carried thereby, said guide strip having a pair of oppositely disposed inwardly extending longitudinal flanges, said flanges forming a slot between their confronting edges, longitudinally extending flanges formed on the guide strip outward of the first mentioned pair of flanges, of a vertically swinging, sliding sash, a sash strip carried by one of the side bars of the sash, said strip having a flange extending along one of its longitudinal edges adapted to interlock and form a weather-tight joint with the adjacent outer flange of the guide strip, the other outer flange of said guide strip being adapted to lie beneath the opposite longitudinal edge portion of the sash strip when the window is in its vertical closed position and form a weather-tight joint therewith, a pivot stud carried by the sash strip and projecting into the slot formed by the confronting longitudinal edges of the first mentioned flanges of the guide strip, and a follower pivotally connected to the sash strip and sliding on the guide strip.
3. The combination with a window frame

and a guide strip located at one side thereof, of a vertically swinging sliding sash, a sash strip carried by the sash, means pivotally connecting the sash strip with the guide strip, a follower connected with the sash strip and sliding over the guide strip, said guide strip, when the window is in its vertical closed position interlocking at its longitudinal edges with the longitudinal edges of the sash strip to form a weather-tight joint at both the inner and outer longitudinal faces of the sash bar, a depressible locking pin on the sash adapted to engage with the adjacent flange of the guide strip to hold the window in its vertical closed position, and a cam strip carried by the guide strip adapted to contact with and depress the locking pin to permit the opening of the window.

4. The combination with a window frame having a guide strip located at one side thereof and provided with inturned double resilient flanges, of a vertically sliding and swinging sash, a link pivoted at one end to the sash, and a cam-like roller constituting a follower carried at the free end of the link and slidably engaging the double flanges of the guide strip, said roller being adapted when the sash is tilted to bind against the guide strip to assist in holding the window stationary in tilted position.

5. The combination with a window frame and a guide strip located at one side thereof and carrying a tripping member, of a vertically sliding and swinging sash, and a movable locking pin mounted in a socket in the sash and adapted when the sash is in its vertical closed position to project outward of the socket and to interlock with the guide strip to hold the window against swinging movement, said pin being movable inward of the sash to unlocking position by engagement with the tripping strip to permit the swinging of the window to open position.

6. The combination with a window frame having a guide strip located at one side thereof, said guide strip having side members provided with longitudinally and centrally extending inturned double resilient flanges, of a vertically sliding sash adapted to slidably engage the guide strip, the double resilient flanges of the strip being adapted to yield to compensate for variations in the width of the frame, due to contraction and expansion of such frame, whereby the binding of the sash against the strip is prevented.

7. The combination with a window frame having a channel guide strip located at one side thereof, of a vertically sliding window sash, a pivot member projecting from one side of the sash into the channel of the guide strip and adapted when the sash is in an-

gular relation to the strip to bind within such strip, a follower within the channel of the guide strip, and a link fixed to the follower and pivoted to the adjacent side 5 of the sash, said follower being adapted to engage and bind against the sides of the channel of the guide strip simultaneously with the binding of the pivot member to as-

sist the latter in holding the sash against movement. 10

In testimony whereof, I affix my signature, in the presence of two witnesses.
